(57) **CLAIM**

The ornamental design for a head lamp, as shown and described.

DESCRIPTION

FIG. 1 is a perspective view of a head lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is another perspective view thereof, shown in an alternate configuration of use.

The broken lines throughout the drawing figures depict portions of the head lamp that form no part of the claimed design.
